UNITED STATES PATENT OFFICE.

JACOB T. CROCKER, OF MULBERRY, ARKANSAS.

SPRING-BOTTOM FOR CHAIRS.

1,111,008.

Specification of Letters Patent. Patented Sept. 22, 1914.

Application filed April 1, 1912. Serial No. 687,674.

To all whom it may concern:

Be it known that I, JACOB T. CROCKER, a citizen of the United States, residing at Mulberry, in the county of Crawford and State of Arkansas, have invented certain new and useful Improvements in Spring-Bottoms for Chairs; and I do declare the following to be a full, clear, and exact description of the invention, such as will enable others skilled in the art to which it appertains to make and use the same.

This invention relates to improvements in spring bottoms for chairs.

One object of the invention is to provide a chair bottom having an improved means for yieldingly attaching the same to the seat frame of a chair.

Another object is to provide a spring bottom for chairs which will be simple, strong and durable in construction and which may be readily applied to new chairs or to old chairs to take the place of the bottoms which may have been broken out of the chairs.

With these and other objects in view the invention consists of certain novel features of construction, and the combination and arrangement of parts as will be more fully described and claimed.

In the accompanying drawings; Figure 1 is a vertical sectional view of a chair showing my improved chair bottom applied thereto; Fig. 2 is a horizontal sectional view of the same on the line 2--2 of Fig. 1; Fig. 3 is a plan view of the seat frame of the bottom.

Referring more particularly to the drawings, 1 denotes the chair to which the improved bottom is applied, said chair comprising the usual seat frame 2, to which is secured the upper ends of supporting legs 3. In the opening of the seat frame 2 is arranged the bottom frame 4 which corresponds in shape to the shape of the opening in the seat frame of the chair and which may be filled in with any suitable material for forming the seat or bottom 5, said seat or bottom being preferably formed of woven

strips of cane, ratan, metal, fabric or any other suitable material having sufficient strength to form said bottom or seat. 56

The bottom frame 4 and the seat or bottom 5 are yieldingly supported in position in the opening of the seat frame 2 at the upper side of said frame by a lower supporting frame 6 to which said bottom frame 55 4 is secured by a series of upwardly and outwardly projecting connecting bars or links 7, any number of which may be employed, said bars or links being preferably loosely connected to the bottom frame 4 and supporting frame 6 by eyes 8 formed in the ends of the bars or links as shown. 60

The supporting frame 6 is secured to the chair and held in position to support the bottom by a series of short coiled springs 9, 65 the inner ends of which are secured to the sides of the supporting frame 6, while their outer ends are secured to supporting rods 10 arranged between and secured at their ends in the legs of the chair a short distance 70 below the seat frame 2 as shown. By thus arranging the supporting frames 6, and the springs 9 it will be seen that the bottom frame 4 and the seat frame 5 will be yieldingly supported in position in the opening 75 of the chair seat frame.

A chair seat or frame constructed in accordance with my invention may be applied to new chairs or to old chairs from which the bottoms have been broken and removed 80 and will form a strong, durable and attractive spring seat for the chair.

From the foregoing description taken in connection with the accompanying drawings, the construction and operation of the invention will be readily understood without requiring a more extended explanation. 85

Having thus described my invention, what I claim is;

The combination with a chair and resili- 90 ent bottom therefor, of a skeleton supporting rectangular shaped frame located below said bottom, angularly disposed depending links movably secured to said bottom the

lower ends of said links being adapted to
slidingly support the frame, supporting
rods for connecting the legs of the chair,
and coiled springs connecting the corners of
the frame and the supporting rods located
adjacent to the links, said springs being in
parallel vertical planes with the depending
links whereby the supporting rectangular
frame is yieldingly and movably held in

proper position in respect to the seat of 10
the chair.

In testimony whereof I have hereunto set
my hand in presence of two subscribing
witnesses.

J. T. CROCKER
